GUNNERY TARGET

Vincent F. D'Agostino and Philip Brieff, Huntington Station, N.Y., assignors to RAI Research Corporation, Long Island City, N.Y., a corporation of New York

Filed Oct. 10, 1968, Ser. No. 13,934

Term of patent 14 years

Int. Cl. D22—99

U.S. Cl. D22—15

FIGURES 1 and 2 are, respectively, the front and side views of a gunnery target embodying our new design.

FIGURES 3 and 4 are, respectively, cross-sectional views through 3—3 and 4—4 of FIGURE 1.

We claim:

The ornamental design for a gunnery target, substantially as shown.
